1,929,000

BED

John M. Line, deceased, late of Springfield, Mo.,
by Mattie D. Line, administratrix, Springfield,
Mo.

Application October 22, 1931. Serial No. 570,437

1 Claim. (Cl. 5—112)

This invention relates to improvements in beds, particularly of the folding or collapsible type which is adaptable for use in connection with automobiles as well as for camping and similar purposes.

An object of the invention is to provide a collapsible bed in which the spacing of the side rails is maintained at a given adjustment by tension members which include partially overlapping components connected by a hook and slot arrangement at their near ends and the legs at their far ends.

Reference is had to the accompanying drawings in which,

15 Figure 1 is a perspective view of the complete bed in one of its positions.

Figure 2 is a perspective view showing the bed wherein the legs of one end are assumed to be folded up and under,

20 Figure 3 is a perspective view illustrating the use of the bed as a back rest,

Figure 4 is a perspective view showing how the bed can be collapsed and rolled into a compact bundle,

25 Figure 5 is a detail view of one of the connecting hinges,

Figure 6 is an inverted perspective view of the bed particularly illustrating the arrangement of the legs and cross tension members,

30 Figure 7 is a fractional perspective view of one end of the bed illustrating a pair of the legs and one of the cross tension members more in detail,

Figure 8 is a fractional perspective view particularly showing how the components of one of the tension members are hooked together,

35 Figure 9 is a fractional perspective view illustrating a slight modification in the mode of connecting the tension member components.

As already indicated, the improved bed is of 40 the folding or collapsible type, this characteristic adapting its use to that of automobile tourists, campers, and any person desiring to temporarily provide a bed of such a nature that it can be folded and rolled into a compact bundle.

45 In a bed of the foregoing nature it is not only desirable to adjust the fabric sheet on which the person actually reclines, so that it will assume a comfortable position between the side rails. One user might desire to have the supporting sheet stretched rather tightly, while another might prefer a pronounced sag. Any adjustment, within reasonable limits, can be made by cross tension members, but these members also have the function of enabling the adjusting out, so to speak, 50 of an undesirable condition of the supporting

sheet. For instance, should the bed have been used so many times that a very objectionable sag may have occurred in the supporting sheet, the cross tension members can be adjusted so as to restore the original cross tension of the sheet.

60

These factors will be clearly understood from the following detailed description. The bed, generally designated 1, (Fig. 1) resembles a cot having longitudinal bars or side rails 2, 3 (Fig. 6) which are coextensive with the length of the bed 65 but are divided in the middle as at 4 (Fig. 6) to produce pairs of halves which, however, are again connected by hinges 5.

These hinges enable folding the bed in the center, the hinge construction being such that the 70 pivotal axis 6 falls below the bottoms of the bars 2, 3 (Fig. 1), thereby insuring a more rigid abutment of the adjacent ends of the bar halves when the bed is set up either as in Figure 1 or 2. The axis 6 coincides with the planes of the ends of the 75 half bars.

A cover 7, previously identified as the supporting fabric sheet, is secured at 8 along its side edges to the side rails 2, 3. The side rails do not have ends as such, thereby leaving the ends of the cover 80 perfectly free and unsupported by anything excepting the cross tension. These unsupported ends are an advantage in that there are no rigid cross parts in the frame to injure the head or feet of the person reclining on the bed.

85

It will thus be understood that the bed frame virtually consists of the side rails 2, 3, there being no rigid head or foot rails as such. Beds of this type are sometimes necessarily made rather short, for instance to enable use thereof inside of an 90 automobile. It is easy to understand that if the frame included head and foot rails these might be in the way of the person lying on the bed to his annoyance and possible injury.

95

Pairs of legs 9, 10 are pivoted to the side rails as at 11 (Figs. 6 and 7). These legs are preferably made of angle material. The ends opposite to the pivots 11 (Fig. 7) are cut out and bent in in such a way as to provide feet 12 which will rest on the ground (Fig. 1) or elsewhere. These feet will prevent possible injury to the fabric of an automobile when the bed is used in connection with the latter. When stood on the ground they will also tend to prevent the legs from sinking in.

100

Braces 13 are permanently pivoted at one end 14 to the respective legs 9, 10, the other end of each brace having a hole 15 (Fig. 6) intended to receive a fixed stud 16, there being a sufficient number of such studs for all of the braces 13.

105

110

After the brace is set in place (Fig. 7) it is held in place on the stud by a cotter pin 17.

These braces establish the extended or open position of the legs 9, 10. The legs will be substantially upright (Fig. 1), but it is preferable that they shall slant outwardly toward the head and foot of the bed so as to make a more secure stand for the bed frame. It will be understood that by removing the cotter pins 17 from the studs 16 the parts can be swung on the various pivots 11, 14 into a nested position within the confines of the side rails 2, 3 as shown at the right of Figure 6.

Cross tension members 18, 19 (Fig. 6) span the pairs of legs 9, 10, serving to maintain a given spacing of the side rails 2, 3 and acting as substitutes for the rigid head and foot cross pieces of the frame. The members 18, 19 perform every function of such cross pieces, but unlike the usual cross pieces, occur both below or in spaced relationship to the cover 7 and are relatively remote from the ends of the cover so that the head and heels of the user are guarded from a hard obstruction.

Each tension member 18, 19 is alike, and the description of the member 18 will suffice for both. This member is made of angle material and comprises two components 20, 21 (Fig. 7). The remote ends are cut away to leave flanges 22 through which the components are pivoted to the legs 9 as at 23, and to provide shoulders 24 which are intended to abut the adjacent edges of the legs 9 and prevent the swinging of the components 20, 21 upwardly (arrows 25) in the direction of the cover 7.

It is permissible to swing the components 20, 21 downwardly, or away from the cover 7, preparatory to collapsing the bed for folding. Were it not for the shoulders 24 there would be the possibility of the components 20, 21 being swung toward the cover 7 at some time, with the likelihood of tearing the cover. The shoulders 24 are produced by simply cutting out a small part of each component, but when the components are pivotally secured the shoulders effectually prevent the undesired upward movement toward the cover as previously mentioned.

The member 18 has what might be called a hook and slot connection between the overlapping near ends of the components (Fig. 7). The component 21 is cut out at 26 (Figs. 7 and 8), then bent to produce a hook 27. This hook is more in the nature of a tongue at right angles to the body of the component 21, but it is quite correct to say that the tongue 27 is hooked into any one of a series of slots 28 in the component 20, thereby to establish the extended adjustment of the tension member 18. A band 29 slidably embraces the member 18 (Fig. 7) and is intended to fit over the ends of the components 20, 21 so as to hold the hook or tongue 27 in engagement with a given slot 28.

Should the user prefer not to have the cover 7 stretched tight across the side rails 2, 3 he can undo the hook and slot connection (Fig. 7) and readjust it so that there will be a more or less pronounced sag in the cover. On the same principle, should the cover be worn into an undesirable sag, the hook and slot connection would be undone and readjusted until the sag disappeared. For this purpose the component 20 (Fig. 7) will be provided with as many slots as will ordinarily be necessary to make any adjustment within reasonable limits. It will be understood that when the band 29 is once slipped toward the center over each component 20, 21 the member 18 (also

the member 19) will be absolutely rigid and serve to maintain the desired cross tension of the cover 7.

It will also be perceived that this function of the tension members 18, 19 will obtain regardless of the positions of the legs 9, 10 and of the bed itself. To this end it is possible to fold either one or both pairs of legs under. When one pair is folded under (Fig. 2) the bed will stand on a gradual incline. One pair of legs can also be folded under in the event that this was necessary to properly stand the bed in certain types of automobiles. When the bed is doubled up in substantial A-form (Fig. 3) it will serve as a back rest for a person sitting on the ground. The adjacent pairs of legs 9, 10 may then be so engaged with the ground as to serve as prongs in order to assist in keeping the bed in its doubled standing position.

Reverting to the hinging together of the bed sections, it is to be observed that the cover 7 is cut away at 30 (Figs. 1 and 2) at places adjacent to the hinges 5, so as to clear the rails 2, 3 and avoid any possibility of the medial pucker 31 (Fig. 6) from getting down between the abutting ends of the side rails and preventing their being opened in line with each other. The requirement of folding the half sections of the bed upon each other makes it necessary to provide a fullness in the center. This fullness disappears as the pucker 31 on the nether side when the bed is open (Figs. 1 and 2), but when the bed is stood as in Figure 3 this pucker stretches across somewhat, and when the half sections are folded upon each other the pucker will be drawn taut.

Figure 9 illustrates a slight modification where-in the band 29 is replaced by a bolt and slot connection in the components 21, 20. The hook 27 and slot 28 arrangement will be the same as before, but in place of the band 29 there will be a bolt 32 in the component 21 and a slot 33 in the component 20. This may be an open-ended slot. When the desired adjustment at 29, 28 is made the nut on the bolt 32 will be driven up tight against the component 20 after having seen to it that the bolt 32 was in the slot 33, thereby to fix the connection.

Upon desiring to collapse the bed as in Figure 4 one has only to slip the band 29 away from the component 20 (Fig. 7) and to loosen the braces 13 from the studs 16. The tension member components 20, 21, legs 9, 10, and braces 13 will all be swung together in the proper direction on their pivots so as to lie against the insides of the rails 2, 3. The half sections of the bed are then swung over on the hinges 5 and rolled substantially into the shape shown in Figure 4.

What is claimed is:—

In a bed having a supporting sheet, side rails to which the sheet is attached, and legs pivoted to the rails; means to maintain the spacing of the side rails hence a given cross tension of the sheet, said means comprising a cross member having partially overlapping components attached to the legs, one of said components having slots, a tongue on the other component to be hooked in one of the slots, and means for bringing pressure to bear on the overlapping ends to maintain the engagement of the tongue with the slot.
